UNITED STATES PATENT OFFICE

130,750

DESIGN FOR A SHIP LAMP

Ray A. Schober, Chicago, Ill., assignor to Premium Products Mfg. Co., Chicago, Ill., a partnership composed of Ray A. Schober and Nate Asher

Application August 21, 1939, Serial No. 86,810

Term of patent 3½ years

To all whom it may concern:

Be it known that I, Ray A. Schober, a citizen of the United States, residing at Chicago, in the county of Cook and State of Illinois, have invented a new, original, and ornamental Design for Ship Lamps, of which the following is a specification, reference being had to the accompanying drawing, forming part thereof.

Fig. 1 is a view in perspective of a ship lamp, showing my new design.

Fig. 2 is a top plan view on a reduced scale of the hull with the deck and masts removed.

The opposite side of the design is substantially the same in appearance as the side disclosed.

I claim:

The ornamental design for a ship lamp, substantially as shown and described.

RAY A. SCHOBER.
